UNITED STATES PATENT OFFICE.

EDWARD A. EVERETT, OF DETROIT, MICHIGAN, ASSIGNOR OF ONE-FOURTH TO JAMES C. MOCK AND ONE-FOURTH TO JAMES J. ROSS, OF DETROIT, MICHIGAN.

CIRCUIT-BREAKER FOR AUTOMATIC SIGNALING APPARATUS

No. 908,654.

Specification of Letters Patent.

Patented Jan. 5, 1909.

Application filed November 9, 1907. Serial No. 401,436.

To all whom it may concern.

Be it known that I, EDWARD A. EVERETT, a citizen of the United States, residing at Detroit, in the county of Wayne, State of Michigan, have invented certain new and useful Improvements in Circuit-Breakers for Automatic Signaling Apparatus; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to a circuit breaking device for automatic signaling apparatus, especially designed for use in connection with relays that are employed in the signal controlling circuits of railway block signal systems, and the invention consists in providing means at the relay for automatically opening the circuit controlling the signals in case of accident to the relay support or housing, or of carelessness or ignorance on the part of some one who might incline or invert the relay, all of which will be hereinafter more fully set forth and pointed out in the claims.

The object of the invention is to provide simple and efficient means for automatically opening the signal controlling circuit so as to set the signals at "danger" when by accident or otherwise a relay supporting post is knocked down or the relay in any way becomes tilted or overturned, the signals remaining at "danger" until the fault is remedied.

As at present constructed, relays which are employed in the circuits controlling the signals will if inclined or overturned close the contacts controlling the signal circuits, thereby maintaining the signals in a position indicating "all clear" even if a train is in the block with which the relay is associated, thereby removing the protection which such train is supposed to have. In the event of a tilted or overturned relay, it is of vital importance that the signal should go to "danger" for if it does not, life and property are endangered. For this reason an automatic circuit breaker is essential.

The importance of protecting the inclosures or housings in which the signal relays are located is so great that some roads have gone to the great expense of erecting heavy

cast iron posts and housings upon concrete foundations to prevent the overturning of the relay through accident to its inclosing box or support. This expensive construction, however, does not prevent the relay being tilted or overturned in some other way; for example, instances have been known where ignorant or careless employees have temporarily inverted relays for the purpose of making tests or locating some trouble in the circuit, thereby removing all protection to a train which might be in the block affected thereby.

The application of this device to the signal relays will remove the dangerous conditions due to such an occurrence because the signals will be set to indicate "stop" and the movement of trains will be governed accordingly.

I have shown the application of my automatic circuit breaker in connection with a standard type of signal relay illustrated in the accompanying drawings, in which:

Figure 1 is a central vertical section through this type of signal relay to which my automatic circuit breaker is applied. Fig. 2 is a plan view of said relay. Fig. 3 is an elevation of a post carrying a box or housing at its upper end in which the relay is located, the dotted lines showing said post tilted out of its normal position. Fig. 4 is an enlarged detail view of one of the binding posts of the relay, showing my circuit breaker connected therewith, said circuit breaker being in section. Fig. 5 is a view similar to Fig. 4 showing the position of parts when the relay is tilted. Fig. 6 is a plan view of the glass mercury cup forming a part of the circuit breaker. Fig. 7 is a fragmentary view in section, showing the manner of connecting the mercury cup with the binding post of a relay when said binding post is originally constructed for this attachment.

Referring to the characters of reference, 1 designates the glass wall of a standard type of signal relay which is confined between the top 2 and the base 3 by suitable tie rods in a manner well understood in the art forming a sealed inclosure in which the operative parts are located. Mounted upon the top of said inclosure are the coils 4 the pole piece 5 of which projects through the top, as shown. The armature 6 is pivotally mounted at 7 and carries the usual conductor arm 8 insu-

lated therefrom by the sleeves 9. At the outer or free end of said arm is a contact spring 10 which is adapted when the magnet is energized to make contact with the point 11 at the lower end of the binding screw 12 to the upper end of which one wire 13 of the signal circuit, not shown, is connected; the other wire 14 of the signal circuit is connected to the rear binding post 15, the lower end of which depends within the inclosure of the relay and has a bracket 16 attached thereto by a screw 17, or other suitable means. The lower end of the bracket 16 is recessed to receive the upper end of the glass mercury cup 18 which is removably secured therein. Said cup is preferably circular in form and is provided with a reduced bottom portion 19 forming a well which normally retains the mercury 20. Projecting downwardly from the bracket 16 through the opening in the top of the mercury cup and normally depending within the mercury is a contact point 21. Located in the bottom of the mercury cup is a contact plate 22 from which leads a conductor wire 23 to the rear end of the conductor arm 8. It will therefore be seen that when the magnet is energized, the signal controlling circuit at the relay is through binding post 15, the bracket 16, the contact point 21, the mercury 20, contact plate 22, the conductor wire 23, the conductor arm 8, the contact point 10, the point 11, and the binding post 12. Upon a deenergization of the magnet the armature will fall carrying downward the arm 8 and breaking the circuit between the points 10 and 11. As ordinarily constructed, the conductor wire 23 extends directly to the lower end of the binding post 15 so that should the relay become inverted or tilted sidewise to any great extent the circuit will not open at the points 10 and 11 because of the lightness of the armature and the friction that would be offered by its hinge or point of pivot when out of a horizontal plane even should the magnet become deenergized, thereby allowing the signal controlling circuit to remain closed and indicating a clear track, when as a matter of fact a train might be occupying the block controlled by said signals. By including my improved circuit breaker in the signal controlling circuit, as shown, a tilting of the relay from any cause sufficient to interfere with its operation will cause the mercury to flow into the side of the cup and away from the contact point 21, as shown in Fig. 5, and expose said contact point, thereby automatically breaking said circuit and placing the signals at "danger". Upon returning the relay to its normal or vertical position, the circuit will be at once restored insuring a continuation of the normal function of the apparatus.

By locating the operative parts within the sealed inclosure of the relay interference

therewith is prevented while the condition of the automatic circuit breaker may at all times be determined through the glass wall of said inclosure.

The bracket 16 employed to connect the circuit breaker with the binding post 15 will be used to attach my improved circuit breaker to relays already in service. Where new relays are made to include my circuit breaker, the lower end of the binding post 15 will be provided with means for attaching the mercury cup directly thereto, as shown in Fig. 7.

It will now be understood that a tilting of the relay or its support or any manipulation thereof or any interference therewith sufficient to affect its normal operation, will at once open the circuit at the relay which controls the track signals, thereby placing said signals at "danger" and preventing the possibility of accident until the trouble can be detected and removed.

The conductor wires 24 and 25 leading to the coils of the magnet indicate the wires of the ordinary track circuit of a block signal system, not shown.

Having thus fully set forth my invention, what I claim as new and desire to secure by Letters Patent, is:

1. In an automatic circuit breaker for signaling apparatus, the combination of a signal controlling circuit, a relay included therein, and means associated with the relay for automatically opening said circuit upon the tilting or inversion of the relay.

2. In a circuit breaking device for signaling apparatus, the combination with the signal controlling circuit, of a relay included therein, a circuit breaker also included in said circuit and associated with said relay, said circuit breaking device comprising relatively movable conductive parts adapted to be actuated to open the circuit by a movement of said relay out of its normal position.

3. The combination with a signal circuit, of a circuit breaker fixed in the circuit to the conductors thereof and having relatively movable conductive parts and a normally operative position, one of the conductive parts of the circuit breaker being movable from the other of said parts to break the circuit upon an incidental movement of the circuit breaker out of its normal position.

4. A circuit breaking device for signaling apparatus, comprising a signal controlling circuit, a relay therein, a circuit breaker mounted on the relay and included in said circuit, said circuit breaker consisting of a cup of insulating material, a contact plate in the bottom thereof from which one of the circuit wires leads, a contact point extending downward into said cup and connected with the circuit wire, a quantity of conductive material in the cup in a fluid state, normally

- covering said plate and point, said cup having an annular chamber into which said fluid may flow upon the tilting thereof and expose said contact point.
5. In a circuit breaking device for signaling apparatus, the combination with a signal controlling circuit, of a relay included therein, a circuit breaker in said circuit, said circuit breaker depending from one of the binding posts of the relay and consisting of a receptacle of insulating material having a contact plate in the bottom thereof from which one of the circuit wires leads, a contact point insulated from said plate and extending into said cup also connected with the circuit wire, a quantity of conductive material in a fluid state within said cup normally covering said plate and point but adapted to flow from and expose said point
- upon a tilting of the relay out of its normally operative position.
6. In a circuit breaking device for signaling apparatus, the combination with a signal controlling circuit, of a relay included therein, a circuit breaker also included in said circuit and attached to the relay, said circuit breaker comprising a fluid conductive element normally connecting the conductive parts and adapted to flow from one of said parts to open the circuit upon a movement of the relay out of its normal position.

In testimony whereof, I sign this specification in the presence of two witnesses.

EDWARD A. EVERETT.
